(57) **CLAIM**

The ornamental design for a ball launcher, as shown and described.

DESCRIPTION

FIG. 1 is a perspective view of a ball launcher;
FIG. 2 is a left side elevational view thereof;
FIG. 3 is a right side elevational view thereof;
FIG. 4 is a top plan view thereof;
FIG. 5 is a bottom plan view thereof;
FIG. 6 is a front elevational view thereof;
FIG. 7 is a rear elevational view thereof; and,
FIG. 8 is a perspective view thereof showing the ball launcher in use.

The broken lines shown in the drawing views are included for the purpose of showing environmental structure that forms no part of the claimed design.
